United States Patent Office.

CHARLES T. MEYER, OF BERGEN, NEW JERSEY, ASSIGNOR TO EDWARD C. SAMPSON, OF NEW YORK, N. Y.

Design No. 2,639, dated April 30, 1867; antedated April 3, 1867.

DESIGN FOR A FLOOR OIL-CLOTH OR CARPET PATTERN.

The Schedule referred to in these Letters Patent and making part of the same.

TO ALL WHOM IT MAY CONCERN:

Be it known that I, CHARLES T. MEYER, of the town of Bergen, county of Hudson, State of New Jersey, have originated and designed a new Pattern for Floor Oil-Cloths, Carpets, or other fabrics, of which the following is a full, clear, and exact description, reference being had to the accompanying specimens or drawings, making part of this specification, and marked or designated as Chintz Pattern No. (143) One Hundred Forty-Three, which is sufficient, without further aid, to enable any person skilled in the art to repeat it for practical use. The colors employed for the different portions of this design may be varied to suit the convenience or taste of the manufacturer.

What I claim as my invention, and desire to secure by Letters Patent, is—

The design or pattern for floor oil-cloths, carpets, or other fabrics, herein set forth and shown.
